UNITED STATES PATENT OFFICE

HARRY NEGBAUR, OF NEW YORK, N. Y., ASSIGNOR TO WM. DEMUTH & CO., A CORPORATION OF NEW YORK

DESIGN FOR A BILL CLIP

Application filed May 24, 1930. Serial No. 35,761. Term of patent 8½ years.

To all whom it may concern:

Be it known that I, HARRY NEGBAUR, a citizen of the United States of America, and a resident of New York, county and State of New York, have invented a new, original, and ornamental Design for Bill Clips, of which the following is a specification, reference being had to the drawing, forming a part thereof.

Figures 1 and 2 are elevational views showing opposite sides of the bill clip; and Figure 3 is an end view of the same.

I claim:

The ornamental design for a bill clip substantially as shown.

HARRY NEGBAUR.
